(57) **CLAIM**

The ornamental design for an LED package, as shown and
described.

DESCRIPTION

FIG. 1 is a perspective view of one embodiment of an LED
package showing my design;
FIG. 2 is a top plan view of the LED package shown in FIG.
1;
FIG. 3 is a bottom plan view of the LED package shown in
FIG. 1;
FIG. 4 is a front elevation view of the LED package shown in
FIG. 1, with the back and both side elevation views being
substantially similar;
FIG. 5 is a perspective view of another embodiment of an
LED package showing my design;
FIG. 6 is a top plan view of the LED package shown in FIG.
5;
FIG. 7 is a bottom plan view of the LED package shown in
FIG. 5;
FIG. 8 is a front elevation view of the LED package shown in
FIG. 5, with the back and both side elevation views being
substantially similar;
FIG. 9 is a perspective view of another embodiment of an
LED package showing my design;
FIG. 10 is a top plan view of the LED package shown in FIG.
9;
FIG. 11 is a bottom plan view of the LED package shown in
FIG. 9;
FIG. 12 is a front elevation view of the LED package shown
in FIG. 9, with the back and both side elevation views being
substantially similar;
FIG. 13 is a top plan view of one component of the LED
package shown in FIG. 9;
FIG. 14 is a bottom plan view of one component of the LED
package shown in FIG. 9;
FIG. 15 is a perspective view of another embodiment of an
LED package showing my design;
FIG. 16 is a top plan view of the LED package shown in FIG.
15;
FIG. 17 is a bottom plan view of the LED package shown in
FIG. 15; and,
FIG. 18 is a front elevation view of the LED package shown
in FIG. 15, with the back and both side elevation views being
substantially similar.
The broken lines in any of FIGS. 1-18 are for illustrative
